6 Claims. (Cl. 37—141)

My invention relates to devices which are moved by power into a body of earth to dislodge the earth and retain it for transportation to another point. Depending largely upon the type of power mechanism utilized to orient and propel the excavator are the details of the design and the particular name given to the excavator. In the power shovel field a cup-like excavator mounted at the end of a dipper stick is usually referred to as a "dipper", whereas in the dredging field where the cup-like excavator is incorporated in an endless chain of similar units, the excavator is usually referred to as a "bucket". While the general features and general principles of my invention make it applicable to all fields of use, I have chosen to describe it herein particularly in connection with its adaptation to dredge installations.

It has become common practice in dredge construction to make the dredge bucket in two general parts. The first of these is a combined hood and back, forming a cup-like structure having pivot pin connections to other structures of like character forming a chain or line of buckets arranged in an endless loop and having an upper run and a lower run extending between upper and lower tumblers. The combined hood and back or base are sometimes referred to as a bucket body and almost invariably are cast in one piece of manganese steel. Cast manganese steel has been almost universally adopted for this use, although the limits or tolerances necessary in manufacture are relatively large, and machining after casting is virtually restricted to superficial grinding operations. Even so, all separate parts must be designed to fit so snugly and tightly when assembled that, even after reasonable wear, they will resist any material relative movement therebetween which would cause greatly accelerated wear. While a bucket body is subject to a great deal of vibration and abuse in dredging service, it is not subject to a great deal of abrasive wear and hence is designed and expected to remain assembled and in service without serious deterioration or difficulty over a protracted period. Bucket bodies vary considerably in capacity, contour, relative size, dimensions, and other factors, depending upon their particular design for conditions under which they are used, but in general they all terminate in a substantially elliptical or approximately elliptical margin. If this margin were directly to excavate and encounter the abrasive material dredged, it would very quickly wear and make necessary the replacement of the entire bucket body.

This difficulty is precluded by the second general bucket part, which is a separate lip, following approximately the contour of the bucket margin preferably for more than a half ellipse in extent and in general extending the contours of the bucket, and fastened to the bucket body with a greater or lesser degree of removability. The usual method of fastening is to provide rivets through overlapping portions of the lip and the bucket, but riveting is not entirely satisfactory. It requires a relatively long time for installation, together with special riveting equipment at the point of installation, while probably the worst drawback is that the rivets, under the severe service to which the excavators are subjected, do not continue for long to hold the lip tightly in engagement with the bucket body. As soon as some creeping or working movement begins, due to looseness and wearing of the rivets, the relative movement between the lip and the bucket body becomes progressively greater, the vibration and shaking become tremendous, and before long the lip is so loose on the bucket body that it must be removed and replaced or reriveted. This operation at the least entails cutting out the worn rivets and reriveting the lip in place. But a great deal of other damage is often done, since the loose rivets likewise accelerate the wear in the bucket body itself which is thus seriously damaged and must be expensively repaired prior to the installation of a new lip.

The riveting and cutting out of rivets and the general difficulties of removal and installation are in many instances increased since some lips carry an outside flange or apron which overlies the outer periphery of the dredge bucket body, some lips carry an inner flange or flanges which overlie all or part of the inner surface of the bucket body to act as reinforcements, and some lips are provided with both inside and outside flanges. In addition to all of this, it many times occurs that only a few buckets in an entire bucket line need repairs or have to have their lips replaced, and it is for that reason especially and under all circumstances highly desirable to be able to replace the lip on a bucket body without in any wise removing the bucket body from the bucket line, hence making it necessary to remove the old lip and to apply the new lip by operating between successive buckets in place in the line.

It is therefore an object of my invention to provide an excavator having a readily removable lip which does not require rivets for fastening.

Another object of my invention is to provide, for a generally elliptical excavator bucket body,

a removable lip extending around more than half of the bucket body periphery and held in place without rivets.

An additional object of my invention is to provide a removable, rivetless lip for an excavator, which can be installed between successive excavators in line.

A further object of my invention is to provide an excavator in which the parts fit tightly without the necessity of accurate machining.

Another object of my invention is to provide an excavating body and lip which have generally improved fastening means.

Another object of my invention is to provide an excavating body having a major axis with a detachable lip extending beyond or past such axis.

A further object of my invention is to provide an excavator body and lip in which the forward ends of the lip are held from rearward movement and the lip is seated to resist digging strains.

An additional object of my invention is to provide a body and lip assembly in which the lip is amply rugged but contains a minimum of metal 25 in order to reduce the amount discarded.

A still further object of my invention is to provide a removable lip for an excavator which can be installed between successive excavators.

The foregoing and other objects are attained 30 in the embodiments of the invention illustrated in the drawings, in which—

Fig. 20 is a perspective side view of the excavator shown in Fig. 19.

Fig. 21 is a perspective front view of the excavator shown in Fig. 19.

In its preferred form, the excavator of my invention includes a bucket body having a substantially elliptical margin with which a removable lip matches, the lip terminating in a pair of horns which have superficial surfaces of revolution mating with surfaces of revolution on the bucket body approximately centered on the major axis thereof, all combined with fulcrum seats for the body and the lip, ledges coacting between the body and the lip horns, and means engaging the lip and the body for springing the lip into seating position on the fulcrum seats and ledges and precluding relative rotation between the body and the lip.

In Figs. 1 to 6, inclusive, there is shown a schematic diagram of a dredge bucket body and lip for descriptive illustration of the features and principles of my invention, but these figures are not intended to disclose a practical embodiment of the invention, necessarily. In these figures many of the dimensions are greatly exaggerated, and the location of various of the parts is distorted from usual practice, for the purpose of illustration. As diagrammatically shown, the excavator body 6 is a cup-like structure having a substantially continuous bounding wall, generally designated 7, having a rear portion 8 and a front portion 9. Since the bucket in use in a continuous conveyor is sometimes upright and sometimes inverted, sometimes travelling from left to right and at other times from right to left, any references herein to upper or lower, forward or rearward, right or left, or horizontal or vertical, are purely relative.

In a cross-section on a transverse, approximately horizontal plane, the contour of the wall 7 is virtually elliptical (see Fig. 5), so that the major axis defining the major vertical plane is represented by the broken line 11. This elliptical contour is by no means mathematically exact, and wherever mathematical terminology is utilized herein it refers approximately to the shapes and contours utilized since, due largely to the casting technique employed, exact accuracy is virtually impossible and variation between successive pieces is often relatively large. Additionally, the design of the bucket varies considerably with the designer's taste and the character of the service and the material to be handled, so that the precise contour of the bucket body margin 12 varies, although it is almost always curvilinear and usually approximates the ellipse shown.

To co-operate with the bucket wall 7 as a removable member, I provide the separate lip 13. This is customarily a cast manganese steel member, matching in contour the margin 12 of the bucket body 6 and preferably of sufficient arcuate extent at least in part to project beyond or around the major axis 11. The lip is thus crescent-shaped or more than semi-elliptic in plan. Although it is preferably fabricated in one piece, the lip 13 can conveniently be thought of as hav- 75

ing a central portion 14, a left-hand terminus or horn 16, and a right-hand terminus or horn 17. The horns extend away from the central portion 14 in the same direction and are approximately, 5 although by no means mathematically, parallel.

I preferably provide means for interrelating the bucket body 6 and the lip 13 in the region of the horns 16 and 17 in such a way that there are large bearing surfaces to resist the principal 10 forces encountered in excavating. These forces are represented by arrows 18 and 19, not intended accurately to represent the precise amount or direction of the forces or their resultants, but to give a general indication of the direction in 15 which some of the major forces act. To provide such mating surfaces so that they can be finished by no more than superficial grinding after casting, and so that they will give a tight interrelationship when mated, I preferably provide on the 20 bucket wall 7, in lateral areas adjacent the major axis 11, lateral seating areas 22 and 23, each of which is preferably a surface of revolution about the major axis 11.

Conveniently, the radius of the surface 22 is 25 R_1 , centering on the major axis 11 and located therefore in the central plane 21, and likewise being substantially concentric with the external bounding surface 24 of the bucket wall the radius of which is R (Fig. 5). The coincidence in contour of the external surface 24 and of the surface 22 of revolution is not necessary but is desirable to give relatively uniform thickness to the wall 7. It is also not at all necessary that the surface 22 of revolution be defined by a constant radius 30 R_1 so that it is spherical, since this surface can be ellipsoidal, hyperboloidal, paraboloidal, or an approximation of any suitable surface of revolution, even flat. It is also not necessary that the axis of the surface of revolution be precisely 35 coincident with the major axis 11 of the bucket body, but a reasonable approximation thereto is desirable. Preferably, the surface 22 of revolution is located at about the mid-point of the thickness of the wall 7.

40 Adapted to mate therewith is a corresponding surface 26 of revolution on the horn 16. This surface of revolution, when the parts are assembled, is preferably concentric with the surface 22 of revolution so that its representative radius 45 R_2 centers on the major axis 11 of the assembly. The character of the surface 26 of revolution is subject to considerable variation, but preferably R_1 and R_2 are made to approach each other as 50 nearly as is commercially feasible for manufac- 55 ture.

As shown in Figs. 1, 4, and 7, a side elevation of the surface 22 of revolution is not a complete circle and may even be elliptical or of contour other than circular, as far as its outline is concerned, but the surface or area 22 preferably constitutes a somewhat lunar, shallow recess 31 in the wall 7, opening upwardly onto the margin 12 of the bucket and being likewise bounded on what approximates a diameter by a ledge surface 60 32 formed by an abutment 33 interposed between the recess 31 and the upper margin 12 of the body. There are thus provided in the bucket body two lateral recesses 31, each being approximately 65 lunar shaped in side elevation, being about half the thickness of the bucket wall, being defined by a surface of revolution approximately centered on the major axis of the bucket, and opening upwardly through the upper margin of the bucket. These shallow recesses are distinct 70 75 from virtually closed pockets since they can be

accurately cast and are open to receive finish grinding tools.

Each of the horns 16 and 17 on the lip 14, characterized by its surface 26 of revolution, is substantially lunar in side elevation to correspond 5 generally with the shape of the recess 31, but the lower margin 36 of the horn is spaced from the margin 38 of the recess so that under no circumstances is there contact therebetween. The inner surface 41 of each horn is preferably substantially a surface of revolution matching the mating surface 26 and characterized by a radius R_3 ; and, although this is not a necessary relationship, it is usually established in order to provide a uniform horn thickness, the general aim 10 being to keep the interior periphery 44 of the lip and the interior periphery 45 of the body 6 substantially continuous, smooth and uninterrupted, so as to facilitate loading and discharge of the bucket. The top of each horn is preferably a 20 flat surface 46, designed to abut the ledge surface 32 on the associated abutment 33, while all of the horn surfaces merge smoothly into the surfaces defining the rectangular cross-section of the remainder of the lip 13. 25

In order that the lip may be appropriately related to and supported on the bucket, I preferably provide, in accordance with my invention, a pair of fulcrum pads 47 and 48, each of which is a segregated area of the margin 12 which projects 30 slightly from the surrounding margin to abut and lie in immediate contact with the undersurface 49 of the lip. When the lip rests upon the fulcrum pads 47 and 48, with the surfaces 46 of the horns 16 and 17 in abutment with the 35 ledge surfaces 32, the lip is substantially located and positioned on the bucket body, since the mating surfaces 22 and 26 of revolution preclude any movement radially of the major axis 11, counterclockwise (Fig. 4) rotation is precluded by 40 the fulcrum pads 47 and the abutments 33, and transverse or lateral movement along the major axis 11 is precluded by the mating surfaces of the two horns. 45

It thus remains to prevent rotation of the lip 13 with respect to the body 6 in a clockwise direction (Fig. 4) when such rotation is not desired. For this reason I provide a pair of lugs 51 on the center portion 14 of the lip and a corresponding pair of lugs 52 on the rearward part 8 of the body wall 7. These lugs are each apertured to receive a fastening comprising a headed bolt 53 and a nut 54. When the nut is screwed tightly upon the bolt, the center portion 14 of the lip is drawn toward the margin 12 of the bucket body, and preferably I leave sufficient clearance between these two so that the arms 16 and 17 act as levers, being drawn down adjacent the center portion 14, fulcruming on the fulcrum pads 47 and pressing tightly against the abutments 33. 55

The tension put upon the bolts 53 is preferably sufficient to introduce spring or a strain into the horns 16 and 17, so that the parts are, due to the resiliency of the removable lip itself, held in place under an initial stress. The lip 13 is 60 finally seated upon the margin 12 to provide a tight joint. This tension manner of assembly, utilizing a slight lever rocking movement on the fulcrums 47, takes care of inaccuracies in casting and finish, and yet assures a tight assembly 65 of the parts. Relative movement between the lip and the body are precluded in all directions, and the excavating or dredging stresses, as indicated by the arrows 18 and 19, are borne by solid, large faces and in no wise are imposed upon the 70 75

fastenings 53. Inside and outside flanges have been omitted from the diagrammatic views in order to simplify them, but such flanges augment rather than vary the means for preventing shifting of the detachable lip on the bucket body.

With the arrangement of removable lip and bucket body described, the general assembly is effected primarily as shown in Figs. 1 to 5, inclusive, wherein the bucket body 6 is assumed to be interposed between a preceding and a succeeding bucket in the upper run of a bucket line. By suitable mechanism for gripping the detachable lip, the lip is first poised above the bucket body, with the horns depending substantially above the lunar recesses. The lip is lowered into position with pads 56 on the lip horns resting upon the abutments 33 on the bucket body. The major portion of the weight of the lip is thus rested upon the bucket body, so that the lip can readily be positioned for further maneuvering without great effort. Following this, the lip is in general rotated about the major axis 11 in at least an approximate fashion, until it passes through the position shown in Fig. 3 and finally occupies the position shown in Fig. 4. In this position the horns are disposed in their respective lunar recesses, the abutting surfaces 46 and 32 are in contact, and the lip is resting upon the fulcrum pads 47. The fastening bolts 53 are then put into position and the fastenings 54 are operated so that the bolts are placed in tension and the lip is sprung into place.

The rotation of the lip into position is followed in reverse order when the lip is lifted out for replacement or for inspection. The fastenings 53 are first loosened and removed, the lip is rotated about the major axis 11 until it occupies substantially a depending position and then is lifted approximately vertically upwards from its relationship with the bucket body, coming free without in any wise interfering with the preceding or succeeding buckets in the line. Throughout both of the operations of installation and dismounting, therefore, the approximate rotary movement of the lip about the major axis 11 of the bucket body is a characteristic. This movement is greatly facilitated by providing the termini of the horns and the lunar recesses with surfaces of revolution.

The surfaces of revolution can be of any contour, even including planar surfaces which can be considered to be surfaces generated by revolution of lines perpendicular to the transverse major axis around such axis. While only a slight curvature of the surfaces is necessary to prevent radial movement of the mating surfaces, nevertheless in the extreme condition where such mating surfaces are true planes it is desirable to provide an additional pair of projections 57 at the margin of the lunar recesses 31 to come virtually into contact with the boundaries 36 of the horns, so that movement of the lip 13 to the left in Fig. 6 is effectively precluded by direct abutment of these surfaces. These faces of the projections 57 in themselves are partial surfaces of revolution, so that, even in the extreme case where the mating surfaces 22 and 26 are flat, there are still surfaces of revolution effective to preclude radial movement of the lip on the bucket body.

The foregoing description is primarily of a diagrammatic arrangement, to emphasize a theoretical relationship of parts which is particularly desirable. In practice, there are usually many factors which become important to modify the general considerations mentioned. In Figs. 7,

8, and 9 there is shown an example of an actual dredge bucket constructed in accordance with my invention and incorporating the various factors disclosed herein as being of advantage. In the practical arrangement, the bucket body 106 itself is not, in cross-section, a true ellipse, although it approximates the elliptical contour, particularly around the left (Fig. 8) side of the major axis 107. In addition, the margin 108 of the body is provided with an exterior ledge 109 on which a depending flange 111 on the lip 112 rests when the lip and the bucket are finally assembled. This flange forms an outside guide and protector on the body, while pads 113 and 114, corresponding to the horns 16 and 17, provide inside flanges. Preferably, the outside flange 111 and the inside flanges 113 and 114 on opposite sides of the body 106 are in overlapping relationship to provide a channel 116 or groove therebetween. The margin 108 of the bucket body itself lies within this channel and is consequently well reinforced and protected by the overlapping flanges against the lateral strains arising in excavating.

The recesses 117 and 118 are shallow and open for convenience in casting accurately and so that all of their surfaces are readily accessible to a grinding tool for finishing purposes. It is found in practice that a pocket or depression which is relatively deep, low and narrow is virtually impossible to cast with any satisfactory degree of accuracy and cannot subsequently be ground to reasonable limits. Consequently, the construction adopted herein, of providing relatively large, shallow and open recesses, permits ready and accurate casting with great facility for subsequent grinding or chipping. Since the recesses are so readily accessible and can be so accurately cast and finished, it is permissible to provide a slightly bevelled surface 119 along the seating pads 121 to abut a comparable bevelled face on the horn flanges 113 and 114, so that, should there be any tendency to dislodge the horn flanges inwardly toward each other, the tendency will be resisted by the inclined or bevelled faces 119. While these faces are slightly bevelled, they are nevertheless available for grinding by an appropriate tool.

Another practical embodiment of my invention is disclosed in Figs. 10 to 18, inclusive. In this arrangement the bucket body or hood 201 is a cast manganese steel structure integral with the bucket link 202 which is characterized by a pair of front bosses 203 and 204 pierced to provide aligned eyes 206 and a rear boss 207 pierced to provide a rear eye 208 for pin connection to adjacent buckets. The bucket body 201 is substantially elliptical in contour, so that its major transverse axis is located approximately as shown by the point 209 in Fig. 10. In general, on one side of the major axis 209 the peripheral margin 211 of the bucket body is enlarged and thickened to provide a seat 212 for a depending outer flange 213 of a detachable lip 214. In general, on the other side of the major axis 209, the body contour varies somewhat but is a smooth continuation of the rearward portion of the body.

On opposite sides of the interior of the body, and approximately centering on the major axis, are lunar recesses 216 adapted to receive mating horns 217 on the lip 214 and having reasonably accurate surfaces of revolution in immediate juxtaposition. The horns are provided with seating extensions 218 which, when the device is assembled or disassembled, are intended to coat

with abutments 219 on the body. Fulcrum seats 221 form bearing pads for the lip, so that fastening bolts 222 are effective to spring the lip somewhat to hold it in position under stress. The 5 fastening bolts are preferably fabricated, as shown in Fig. 12, with enlarged, flattened, conical heads 223 adapted to seat in complementary recesses in sockets 224 on the lip, and are engaged by nuts abutting lugs 226 on the body 201.

10 Adjacent the fastening bolts 222 I preferably provide integral with the hood 201 a pair of guide fins 227 which are intended primarily to coat with the next succeeding bucket when the buckets are inverted around the upper tumbler, 15 in order to guide the material discharged or spilled from the next succeeding bucket. Thus, in effect, the pins 227 on one bucket are functional continuations of the discharge surfaces of the succeeding bucket.

20 A further modified practical embodiment of the invention is disclosed in Figs. 19 to 21, inclusive, in which the bucket body 306 includes an integral hood 307 and a link structure 308 having aligned front eye apertures 309 and a rear eye 25 aperture 311. The body 306 is generally elliptical in a transverse cross-section and terminates in a curvilinear, somewhat elliptical margin 312 having a seat 313 for a matching lip 316. The lip is provided with a pair of horns 317 and 318 30 which, instead of having surfaces of revolution interiorly of the hood, are provided with suitable surfaces of revolution 319 interiorly of the horns but exteriorly of the hood, terminating in abutting surfaces 321 arranged to engage with ledges 322 on the exterior of the bucket structure. The outside of the bucket body 306, consequently, has mating surfaces of revolution and is also provided with fulcrum seats 323 as in the case of the inside horn. The recesses in the outside of the 40 body are equally available for accurate casting and grinding for finish, since they are relatively shallow, wide and long. They are likewise preferably somewhat chamfered or bevelled in order to provide a lateral interlock between the projecting horns and the bucket body, and in general follow out the principles of the inside horn except for the fact that they are located exteriorly of the body.

The interior of the body is provided, preferably, with recesses 324 in which depending flanges 326 are situated. These flanges preferably have considerable clearance with the interior of the bucket body and with the margins of the recesses, although they also are preferably defined by surfaces of revolution approximately mating with corresponding interior surfaces of revolution in the recesses 324. The interior depending flanges assist in protecting the interior of the bucket against abrasive wear and also provide extra reinforcement at the lateral portions of the bucket wherein deformation due to digging stresses on the lip tends to be greater.

The manner of assembly and disassembly of the outside horn lip is substantially the same as 65 with the inside horn; that is, each horn has a projecting portion 327 which can be rested upon the shoulder 328 of the abutment on the body forming the ledge 322, and can then be substantially rotated into assembled position with the 70 abutting surfaces 321 and 322 in intimate contact, with the lip seated upon the fulcrum pads 323, and with suitable bolt fastenings 329 in tension to hold the lip in position on the bucket under stress of its inherent resiliency. Various 75 other features of construction of my detachable

lip and body construction are in general followed in this arrangement.

The general characteristics of all of the embodiments of my invention include surfaces of revolution about which the detachable lip and the body are relatively rotated for assembly and disassembly, for holding the lip against dislodgment in all directions of possible motion except rotation in one direction, and include holding the lip and the body against relative rotation in such direction by fastening means which place the lip under inherent spring tension on the body. The construction is further characterized by the provision of open recesses for interlocking with horns on the lip, so that the construction and the finishing of the bucket and the lip are both attended with considerable practical facility.

I claim:

1. An excavator comprising a bucket body having an upper margin adapted to receive a detachable wearing lip, there being a pair of facing recesses in the inner sides of said body, each recess being in part spaced from said margin to form an abutment between said recess and said margin and in part opening upwardly at said margin, a detachable wearing lip adapted to seat on said upper margin, a pair of enlarged horns depending from the inner sides of said lip substantially occupying said recesses and contacting said abutments, a flange depending from the outer side of said lip and abutting the sides of said body to resist lateral thrusts tending to dislodge said horns from said recesses, and fastening means for holding said lip on said body.

2. An excavator comprising a bucket body having an upper margin adapted to receive a detachable wearing lip, there being a pair of facing recesses in the inner sides of said body each of said recesses being bounded by a substantially semi-circular wall and a radial wall to provide an upward opening to said margin and a ledge between said recess and said margin, a detachable wearing lip adapted to seat on said upper margin, a pair of substantially semi-circular horns depending from the inner sides of said lip to occupy said recesses and abut said ledges, means depending from said lip and abutting the outer sides of said body to resist lateral dislodgment of said horns from said recesses, and fasteners for drawing said lip into tight abutment with said body.

3. An excavator comprising a bucket body having an upper margin adapted to receive a detachable wearing lip, a detachable wearing lip adapted to seat on said upper margin, a flange depending from the exterior of said lip and abutting the sides of said body, a pair of horns each depending from the inside of said lip at the sides thereof to overlap the ends of said flange, there being substantially semi-circular recesses in the inner side walls of said body to receive said horns with the exposed surface thereof substantially flush with the inner surface of said body, and fastening means for holding said lip and said body in abutment.

4. An excavator comprising a bucket body having an upper margin adapted to receive a detachable wearing lip, the material receiving portion of said bucket being single-walled throughout and having a pair of inner recesses in the sides of the body facing each other and opening to said margin, each recess having a boundary which is in part substantially semi-circular and in part substantially radial leaving a ledge between said recess and said margin.

5. An excavator comprising a detachable C-shaped wearing lip for a bucket body, an exterior flange depending from the central portion and the sides of said lip and a pair of horns depending from the inner sides of said lip, each of said horns having a substantially semi-circular contour below the sides of said lip and a substantially radial portion adapted to abut an overhanging ledge on said bucket body.
- 10 6. An excavator comprising a bucket body having an upper margin adapted to receive a detachable wearing lip, there being a pair of facing

recesses in the inner sides of said body, each of said recesses being bounded by a substantially semi-circular wall and a radial wall to provide an upward opening to said margin and a ledge between said recess and said margin, a pair of substantially semi-circular horns depending from the inner sides of said lip to occupy said recesses and abut said ledges, and fastening means for drawing said lip into tight abutment with said body.

10 THOMAS C. WHISLER.
